COMBINED BELT BUCKLE AND BOTTLE CAP REMOVER

Robert Case Dennison, Manchester, Conn.

Application March 1, 1946, Serial No. 651,160

1 Claim. (Cl. 24—178)

1

This invention relates to belt buckles and has for its object to provide a belt buckle with portions shaped and adapted to fit over a bottle cap in such a manner that the buckle is usable as a bottle cap remover.

The usual buckles generally include side portions and forward and rearward end cross-bar portions serving to retain the side bar portions in spaced relationship, providing thereby space through which the end of the belt is extended when fastening the same to the buckle. On the rearward end cross-bar portion there is pivoted a pin which extends forwardly and is adapted to extend through holes in the belt and cooperate with the forward end cross-bar portion to retain the belt end within the buckle. Such a construction is not of itself adapted for removal of a bottle cap remover.

According to the present invention an intermediate cross-bar portion is disposed between the side portions and spaced from the forward end cross-bar portions such distance as to receive the bottle cap. When the buckle is so placed on the bottle cap the forward end cross-bar portion rests on the top of the same and the intermediate cross-bar portion engages with the bottom edge of the cap so that as the buckle is lifted upwardly about the forward cross-bar as a pivot, the cap is lifted from the bottle.

So that the intermediate cross-bar portion will not interfere with the normal operation of the retaining pin, it is depressed downwardly from the sides thereof and sufficiently removed so that the forward end of the pin can engage with the forward cross-bar portion when the belt end is in place. The rearward end cross-bar portion has a handle portion formed thereon which is adapted to extend rearwardly so as to give adequate length to the buckle for its efficient use as a bottle cap remover. This handle portion is such that it can be concealed by the loop of the belt as it is fixed to the rear of the buckle.

For other objects and for a better understanding of the invention, reference may be had to the following detailed description taken in connection with the accompanying drawing in which

Fig. 1 is an illustrative view showing the application of the buckle to a bottle cap, the buckle being shown in longitudinal cross-section in order that the lifting edge of the intermediate portion can be observed;

Fig. 2 is one plan view of the buckle, partly in section, looking generally in the direction of arrow 2 of Fig. 1;

Fig. 3 is a plan view of the buckle and cap as

2

shown in Fig. 1 and looking in the direction of the arrow 3;

Fig. 4 is a cross-sectional view taken at the line 4—4 of Fig. 2 and looking at the lifting edge of the depressed intermediate portion which is adapted for engagement with the bottom edge of the cap;

Fig. 5 is a side elevational view of the buckle with the belt end in place and retained by the pivoted pin, the belt end passing between the forward and intermediate portions of the buckle.

Referring now to the figures, there is shown a bottle 10 having a bottle cap 11 with a top 12 and a bottom edge 13. The bottle cap 11 rests upon a bottle neck 14 in such manner as to normally seal the contents of the bottle from the atmosphere. The cap 11 thus has a tight grasping fit upon the bottle neck 14.

A belt buckle 15 is provided for a belt 16 which buckle has side portions 17 and 18 and forward and rearward end cross-bar portions 19 and 20. The cross-bar portions are of sufficient width as to permit the passage of a belt end 22, Fig. 5, between the side portions 17 and 18. On the rearward portion 20 there is pivoted a pin 21 extending forwardly to engage with the forward cross-bar portion 19. This pin extends through holes in the belt end in the usual fashion and engages with the cross-bar portion 19 to prevent the withdrawal of the belt end 22 when the buckle is being used in its usual manner.

The buckle 15, however, is further provided with an intermediate portion 23 having a lifting or cap engaging face 24 adapted to engage with the bottom edge 13 of the cap 11 when the buckle is fitted upon the cap to be used as a bottle opener. The spacing between the cross-bar portion 19 and the intermediate portion 23 is such as to receive one edge of the cap 11 and to permit the cross-bar 19 to lie upon the top 12 of the bottle cap. The face 24 is inclined so as to lie flush with the bottom edge 13 of the cap when the buckle has been applied to the cap, Fig. 1.

The intermediate portion 23 is depressed downwardly from the side portions as indicated more clearly in Fig. 4 so as not to interfere with the operation of the pin 21 when the buckle is used to receive the belt end 22. In other words, the portion 23 is depressed so as to provide a recess through which the pin 21 can extend for engagement with the forward end portion 19 when the buckle receives the belt end 22.

In order that sufficient leverage can be had to assist in the lifting of the cap from the bottle, there is provided on the rearward or final end

cross-bar portion a rearwardly extending handle portion 25. This handle portion 25 runs co-extensively with the general contour of the buckle and is so formed that it can be concealed by a loop 26 of the belt as it is attached to the buckle and connected by a fastener pin 27. In order that additional fastener pins may be provided, without sacrificing any of the handle length the rearward end of the handle may be notched as indicated at 28 in Fig. 2.

It should now be apparent that there has been provided a belt buckle which can be used as a bottle cap remover by making use of certain of the portions of the usual buckle and providing with such buckle other portions adapted to enter into the lifting of the bottle cap but so fashioned on the buckle as not to interfere in any way with the operation of the buckle upon receiving the belt end.

I have described what I believe to be the best embodiments of my invention. I do not wish, however, to be confined to the embodiments shown, but what I desire to cover by Letters Patent is set forth in the appended claim.

I claim:

A belt buckle adapted to serve as a bottle cap remover and comprising spaced side portions, a forward end cross-bar portion extending fully across to said side portions, a rearward end cross-bar portion, an intermediate cross-bar portion

extending fully across to said side portions and serving to fit under the bottom edge of a bottle cap while the forward end cross-bar is on top of the cap, a pin pivoted on the rearward end cross-bar portion and adapted, when the belt end is introduced between the forward and intermediate cross-bar portions and by passage through a hole in the belt end to engage the forward cross-bar portion to retain the belt end in position, and a narrower handle tongue-like portion forming an integral rearward extension of the rearward cross-bar portion for providing lifting leverage for the buckle as it is used to remove a cap, said handle portion being shaped to be concealed by an attachment loop of the belt.
